UNITED STATES PATENT OFFICE.

MARTIN SCHILDE, OF NEW ORLEANS, LOUISIANA.

VALVE MECHANISM.

SPECIFICATION forming part of Letters Patent No. 752,472, dated February 16, 1904.

Application filed July 11, 1903.

Serial No. 165,041. (No model.)

To all whom it may concern:

Be it known that I, MARTIN SCHILDE, a citizen of the United States, and a resident of New Orleans, in the parish of Orleans and State of Louisiana, have invented a new and Improved Valve Mechanism, of which the following is a full, clear, and exact description.

The invention relates to locomotive-engines, and more particularly to valve mechanisms, such as shown and described in the application for Letters Patent of the United States, Serial No. 150,731, filed by me April 2, 1903.

The object of the invention is to provide a new and improved valve mechanism which can be readily applied to locomotive-engines as now constructed and which is more especially designed to allow the engineer to use the motive agent in both ends of the cylinders for starting purposes or on either end of each cylinder only when running either forward or backward, thus saving a large amount of motive agent and fuel without an appreciable decrease in the propelling power.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a longitudinal sectional elevation of the improvement, showing the shiftable valve-seat in position for admitting live motive agent to both ends of the cylinder when starting the engine. Fig. 2 is a like view of the same, showing the valve-seat shifted to admit live motive agent to the forward end of the cylinder only while running in a backward direction. Fig. 3 is a similar view of the same, showing the valve-seat moved to a position for admitting live motive agent to the rear end of the cylinder when running forward. Fig. 4 is a cross-section of the same on the line 4-4 of Fig. 2. Fig. 5 is a perspective view of the inverted cylindrical portion of the shiftable valve-seat. Fig. 6 is a perspective view of the base-plate for the shiftable valve-seat. Fig. 7 is a side elevation of

the shiftable valve-seat, and Fig. 8 is a side elevation of a locomotive provided with the improvement.

In each cylinder A of the locomotive-engine is mounted to reciprocate a piston B, connected by a piston-rod B' with the locomotive-drivers in the usual manner, so that further description thereof is not deemed necessary.

The cylinder A is provided with steam-admission ports a and b and an exhaust-port c, and the said ports a, b, and c lead to a face A' in a steam-chest A², and on the said face A' is shiftably mounted a valve-seat C, consisting, essentially, of a base-plate C' and a cylindrical portion C², containing a piston slide-valve D, connected by its valve-stem D' with the link-motion under the control of the engineer in the cab of the locomotive in the usual manner. (See Fig. 8.)

The valve-seat C is provided on its base-plate C' with a valve-stem C³, connected with link-and-lever mechanism (see Fig. 8) under the control of the engineer in the cab of the locomotive to enable the engineer to shift the said valve-seat C either to the central position (shown in Fig. 1) whenever it is desired to take steam in the ordinary way at both ends of the cylinder at the time the engine is started or to enable the engineer to shift the said valve-seat C into the position shown in Fig. 3, so that steam is admitted to the rear end of the cylinder A only at the time the locomotive is running in a forward direction, or to enable the engineer to move the said valve-seat C into the position shown in Fig. 2 to take steam only at the forward end of the cylinder at the time the locomotive is running backward.

For the purposes above described the valve-seat C is provided at or near its middle with a central port d, adapted to register either with the exhaust-port c, as shown in Fig. 1, or with the cylinder-port b, as shown in Fig. 2, or with the cylinder-port a, as illustrated in Fig. 3. On opposite sides of this central port d are arranged ports e and f, made L shape and in such a manner that the horizontal member of each port is elongated in a lengthwise direction for the port e to connect the cylinder-port a with the exhaust-port c, as

shown in Fig. 2, and for the port *f* to connect the cylinder-port *b* with the exhaust-port *c*, as shown in Fig. 3. The vertical members of the ports *e* and *f*, as well as the central port *d*, open into the inner cylindrical surface of the portion *C*² of the valve-seat *C* to be controlled by the piston-valve *D* in the usual manner.

Now by reference to Fig. 1 it will be seen that when the valve-seat *C* is in a central position steam is admitted from the steam-chest *A*² to the ends of the cylinder *A* in the usual manner on the reciprocation of the balanced piston slide-valve *D*, actuated in the usual manner from the link mechanism under the control of the engineer. When the engine is started and is running in a forward direction, then the engineer shifts the valve-seat *C* to the position shown in Fig. 3, so that the live motive agent is now only admitted by way of the registering ports *d* and *a* into the rear end of the cylinder *A* whenever the piston slide-valve *D* uncovers the port *d*. Now the piston *B* is forced forward only by the live motive agent passing into the rear end of the cylinder *A* at the time the wrist-pin of the driver travels in the upper half of its travel. The forward end of the cylinder *A* is connected by way of the ports *b* and *f* with the exhaust-port *c* during both the forward and backward strokes of the piston *B*, and hence when the piston moves forward compression of air in the forward end of the cylinder is prevented, and when the piston *B* is on the return stroke then the piston slide-valve *D* is shifted to such a position as to connect the port *f* with the port *d*, so that both ends of the cylinder are now connected with the exhaust-port *c* for the steam to escape from the rear end of the cylinder and for air or steam to pass into the forward end of the cylinder to prevent the formation of a vacuum therein. When the engine is running backward, the engineer shifts the valve-seat *C* to the position shown in Fig. 2, and the live motive agent in the steam-chest *A*² now passes through the ports *d* and *b* into the forward end of the cylinder *A* to push the piston *B* backward therein at the time the wrist-pin of the driver travels in the upper half of its travel. The piston slide-valve *D* in its travel in the valve-seat *C* alternately uncovers the port *d* for the admission of steam and connects the ports *a* and *b* with each other for the exhaust of the steam from the rear end of the cylinder, so that when the piston *B* is on the return stroke then both ends of the cylinder are connected with the exhaust-port *c* to allow escape of the exhaust-steam from the forward end of the cylinder and to allow the rear end of the cylinder to fill with a fluid (air or steam) to prevent a vacuum therein during the return stroke of the piston.

Now when the locomotive is running in a forward direction and the valve-seat *C* is in the position shown in Fig. 3 then the power

of the motive agent is transmitted from the piston *B* to the wrist-pin on the driver only at the time the wrist-pin travels in the upper half of its travel, and during the time the wrist-pin travels in the lower half of its travel the motive agent is shut off, and consequently the power exerted in a rearward direction on the said wrist-pin, and consequently on the locomotive, is dispensed with. In a like manner when the engine is running rearward and the valve-seat *C* is in the position shown in Fig. 2 a like saving of power is obtained, as the cylinder takes steam only at one end and during the time the wrist-pin of the driver travels backward in the upper half of its travel.

From the foregoing it will be seen that in general running of the locomotive the motive agent is at all times shut off while the wrist-pins of the drivers travel in the lower portions of their travels, and the power is only applied when the wrist-pins travel in the upper half of their travels, whether the locomotive is moving forward or backward.

From the foregoing it is evident that a large amount of steam or other motive agent is saved in the running of the locomotive, and consequent wear and tear of the boiler is correspondingly reduced and less fuel is required for generating the amount of steam necessary.

Having thus described my invention, I claim as new and desire to secure by Letters Patent—

1. A locomotive-engine having a manually-controlled cylindrical valve-seat, provided with a flat outer face, mounted to slide on a face for the cylinder-ports, the said valve-seat having ports adapted to register with the cylinder-ports, to admit live motive agent either to both ends of the cylinder or to either end only, and a piston-valve coacting with the said cylinder valve-seat, as set forth.

2. A locomotive-engine having a manually-controlled cylindrical valve-seat, provided with a flat outer face, mounted to slide on a face for the cylinder-ports, the said valve-seat having ports adapted to register with the cylinder-ports, to admit the motive agent either to both ends of the cylinder or to either end only, and a balanced piston-valve mounted to slide in the cylindrical portion of the said valve-seat, as set forth.

3. A locomotive-engine having a manually-controlled valve-seat comprising a flat base-plate and a cylindrical piston valve-seat portion moving with the base-plate, the latter having a central port and elongated end ports, and the said cylindrical piston valve-seat having a central port in register with the said central port in the base, the said cylindrical piston valve-seat portion also having end ports in register with the inner ends of the said base-plate end ports, to form with the latter L-shaped ports, as set forth.

4. A locomotive-engine having a piston slide-valve, and a manually-controlled seat for the said piston slide-valve, the said seat being

provided with a central bore and L-shaped admission-ports on opposite sides of the said central bore, the horizontal members of the admission-ports being elongated in a lengthwise direction, for engagement with the cylinder admission-ports and the cylinder exhaust-port, and the vertical members of the said admission-ports and the said central port opening into the cylindrical portion of the

said seat containing the said piston slide-valve, 10 as set forth.

In testimony whereof I have signed my name to this specification in the presence of two subscribing witnesses.

MARTIN SCHILDE.
